UNITED STATES PATENT OFFICE.

THEODOR H. J. LECKBAND, OF ADAIR, IOWA.

GAS-METER.

SPECIFICATION forming part of Letters Patent No. 645,365, dated March 13, 1900.

Application filed December 7, 1898. Renewed August 28, 1899. Serial No. 728,765. (No model.)

To all whom it may concern:

Be it known that I, THEODOR H. J. LECKBAND, a citizen of the United States, residing at Adair, in the county of Adair and State of Iowa, have invented certain new and useful Improvements in Gas-Meters; and I do hereby declare the following to be a full, clear, and exact description of the invention, such as will enable others skilled in the art to which it applies to make and use the same.

The object of my invention is to provide a measuring instrument or meter of reliable efficiency which will automatically and with absolute accuracy measure the gas as it is consumed.

The details of my invention will be fully set forth in the following specification and illustrated in the accompanying drawings, in which—

Figure 1 is a side elevation showing my improved gas-meter complete. Fig. 2 is a central vertical section of the parts thereof. Fig. 3 is a detail view showing one of the sealing devices in section. Fig. 4 shows a similar view to that presented in Fig. 2. Fig. 5 is a perspective detail of the several seals, while Fig. 6 is a horizontal section of Fig. 4, as indicated by line *xx* on Fig. 4.

Gas-meters as now constructed, so far as I am aware, have their efficiency more or less affected or curtailed by reason of the fact that some of the working parts thereof come directly in contact with the gas, and as the gas is liable to deposit a gummy substance or coal-tar said parts are more or less clogged and disturbed in the performance of their office.

In my invention it will be seen that none of the working parts, as the pivotal points or bearings, can be affected by such deposit, inasmuch as they are entirely outside of the path of the gas, the same being grouped in compact form, and, if necessary, may be protected by a suitable hood or housing.

The several parts of my invention and the accessories required to clearly illustrate the use thereof will be designated by numerals, the same numeral being applied to the same part throughout the several views.

Referring to the drawings, 1 indicates the base or supporting-platform, which may be secured in position where it is desired to lo-

cate the meter, and upon said base I erect, preferably upon either side thereof, the supporting-standards 2, while on each end of the base thus provided I erect the gas holders or measures, which may be made of any preferred size, said measures consisting of the usual telescoping gas-holders, having the base or body-section proper, 3, and the telescoping section 4.

Secured to the central portion of the inner side of each of the lids or top sections 5 are the depending sleeves 6, as is usual, it being understood that suitable apertures 7 are to be provided in the upper end of said sleeve. Designed to telescope with the sleeve 6 are the service-pipes 8 and 9, the former being disposed upon the left, while the latter is shown upon the right section of the drawings, it being understood that each of said pipes is designed to loosely reciprocate within the sleeves 6, and, as usual in such construction, are for the purpose of providing a seal formed by means of the liquid 10 in order that the gas may be held within the upper portion of the telescoping section or bell 5.

It will be seen that the service-pipes 8 and 9 extend outward from each of the tanks or gas-holders and unite at the point where the burner 11 is attached, and each of said pipes is designed to alternately supply said burner, as will be hereinafter fully set forth.

Designed to automatically close and open the service-pipes 8 and 9 and to insure that the supply of gas will be alternately directed into one and the other gas-holder I provide the sealing-cups 12, 13, 14, and 15, the two former being carried upon the pivoted bar or lever 16, while the two latter are carried by the pivoted bar or lever 17.

Disposed parallel with and beneath the upper ends of the pipes 8 and 9 is the connecting-pipe or auxiliary section 18, extending from said pipe 8 to pipe 9, and thus opening communication between them. Depending from the upper ends of the pipes 8 and 9, respectively, are the branches 19 and 20, which are preferably tubular or a mere extension or open-ended branch of said pipes, each branch being provided with a centrally-disposed partition-wall 21 of less extent or reach than the walls of the branch in which they

are mounted, it being clear that said partition will act as a seal when the end of the branch is inserted in their respective sealing-cups, it being understood that any suitable variety of sealing liquid 22—as mercury, &c.—is carried in said cups in sufficient quantity to reach up to the partition or diaphragm 21 when the cup is in an elevated position, as will be more particularly referred to.

10 By reference to Fig. 2 it will be seen that the pivoted bars or levers 16 and 17 are pivotally mounted upon the transversely-disposed rods 23, both of said rods being carried by the standards 2, while near the upper end of said standards I locate the bar 24, upon which I pivot the controlling-lever 25, which is provided with the standard 26 and weight 27, respectively, said standard being disposed at right angles to the plane of the controlling-lever 25. In each end of said lever I mount the screws 28, the office of which will be clearly set forth. Upon the upper edge of each of the bells or telescoping sections 5 I provide the flange 29, which may 15 extend annularly in around the top of the bell or be limited in extent sufficiently to cover the inner edge only thereof, its office being to engage the lever 25 or the set-screws carried thereby, and thus tilt the weight 27 20 toward the bell in contact with said lever.

Pivotedly secured to one end of the lever 17 is the standard 30, which is held in an upright position by means of the bracket 31, attached to the pipe 8, while upon the opposite end of said lever is pivotally secured a similar standard 32, held in a vertical position by the bracket 33, attached to a contiguous part of the pipe 9, both of said brackets loosely receiving their respective standards and permitting them to freely move longitudinally in order that either of them may coöperate with the controlling-lever 25, as will be made clearly apparent in the statement of the operation of my invention. Each of the levers 45 16 and 17 is provided at the pivotal point thereof with a standard and weight 34, the same being disposed at right angles to said levers and designed to occupy a dead-center above the pivot-point of the levers when 50 the lever carrying it is in a horizontal position. The office of the weights 34 is therefore to more positively hold their respective levers in a tilted position, and thereby insure against the casual displacement of the 55 seals, inasmuch as considerable force will be required to depress either of the standards 30 or 32.

In Fig. 2 I have shown a collar 35, secured at a certain point upon the service-pipes 8 60 and 9, and also illustrate an internally-directed flange 36 upon the ends of the sleeves 6, the purpose of said parts being to limit the upward movement of the bells, though, as will be seen in Fig. 1, I am enabled to entirely 65 dispense with said collars and flanges by the use of the controlling rods or levers 37, pivotally connected at their inner ends to the

standards 2, as indicated at 38, the free ends of said rods being pivotally connected to the guiding-arms 39, each of which extends upward into pivotal union with the upper end of the bells 5, and in order to guard against the rotation of said bells I prefer to provide the brackets or guides 40, through which the rods 39 are designed to freely pass, 70 and it is therefore clear that if this construction just described is adopted then the collars 35 and flanges 36 may be dispensed with. In case said collars and flanges are omitted and the controlling-rod 37 and arms 80 39 are relied upon it will be unnecessary to extend the flange 29 entirely around the top of the bells, as a simple projecting arm or bracket upon the inner side of the bell will be all that will be necessary to insure proper 85 coöperation with the controlling-lever 25, whereby said lever may be forced downward into engagement with one of the standards 30 or 32. It is obvious that the set-screws 28 may be employed to render the adjustment 90 of the lever more perfect with respect to the action of the flange 29.

A suitable register or indicator 42 is provided, and said indicator is actuated by means of a pawl or detent 43, carried by the link 41, 95 it being clear that every other tankful only will be registered, though it is further obvious that suitable clutch mechanism might be provided which would insure that each tankful would be registered and that since said tanks 100 or bells may be made so as to hold five, ten, or twenty feet of gas, more or less, the measurement would be for the actual quantity consumed.

The purpose subserved by the weights 27 105 and 34 is to give a more positive action to the parts to which they are attached, it being readily apparent that as said weights fall to one side or the other from the dead-center the action of the parts will be more prompt 110 and positive in character.

By reference to Fig. 2 the operation of my improved gas-measuring machine will, it is thought, be clearly apparent, though a brief statement of such operation may be considered pertinent at this time. It may therefore be said that one of the bells in Fig. 2 is shown to be in a depressed position, signifying that it is nearly empty, though the burner is still being fed therefrom through the pipe 8, as 115 indicated by the travel of the arrows, the sealing-cup 12 being shown in a depressed position, thus leaving the gas free to flow through the pipe 8 and under the partition 21, which is shown to be in clearance of the sealing liquid contained in said cup, and it follows that when the gas has been consumed sufficiently to permit the bell from which said pipe feeds to be lowered sufficiently to cause the flange 29 thereon to strike the end of the lever 25 or the 120 set-screw carried thereby said lever will be depressed and will strike the end of the standard 30, forcing the cup 14 downward and incidentally raising cups 15 and 12 and lowering cup 130

13, said action being induced by the connecting rod or link 41. The rod 41, as will be seen, is pivotally connected to the levers 16 and 17 upon opposite sides of their respective pivot-points, thus insuring that said levers will be simultaneously though oppositely moved—that is to say, when the lever 30, for instance, is depressed, carrying with it the end of the lever 17 to which it is attached, the corresponding end of the lever 16 will be elevated, while the opposite ends of said levers will be correspondingly moved. The opposite end of the lever 17 being elevated will cause the corresponding end of the lever 16 to be depressed. The position in which the rod 17 is disposed, as indicated in Fig. 2, will insure that the sealing-cup 12 will be lowered, thus permitting the free flow of the gas to the burner through the pipe 8, and while said parts are in said position the supply-pipe will feed into pipe 9, which will deliver the gas through the sleeve 6 into the elevated bell through the apertures 7. It is further obvious that when the end of the lever is forced downward into contact with the standard 30 the sealing-cup 14 will be lowered and the sealing-cup 12 simultaneously elevated, which results in cutting off further flow to the burner through pipe 8 and also cutting off a further flow from the supply-pipe 42 into pipe 9 through the sealing-cup 15, inasmuch as said cup will be elevated at the instant the cup 12 is elevated, which results in conveying the gas from pipe 44 directly through the seal 14, which is opened by the action above referred to, and thence into pipe 8 and into the empty bell 5, at the same instant causing the flow of gas from the filled bell 5 upon the right-hand side of the drawings to flow upward through pipe 9 and through the opened sealing-cup 13 and thence to the burner. By connecting the bells in the manner set forth by means of the rod 37 the pressure in the pipes is insured in both bells, and the burner is therefore not wholly dependent for a sufficient pressure alone upon the weight of the bell feeding it.

While it is thought that excellent results will follow the use of the construction set forth in Figs. 1 and 2 and involved in the production of the seals, yet I desire to call attention to another form of construction of these parts, as illustrated in Figs. 4, 5, and 6, wherein it will be seen that in lieu of the several pipes 8 and 18 I provide the solid casting or body 45, which by reference to Fig. 6 will be seen to be provided with the several bores 46, 47, 48, and 49, all properly connected with each other, as by the laterals or branches 50, the bores 46 and 49 being provided near each end thereof with the sealing-sleeves 51, 52, 53, and 54, each having a vertical partition 55 of shorter length than its respective sleeve and corresponding to the partitions 21 of the sleeves 19 and 20 and to the partitions 21^a of the sleeves 19^a and 20^a, all of said parts being substantially identical

with each other and designed to subserve the same purpose.

The bores 47 and 48 are provided, respectively, with the extensions or necks 56 and 57, each being designed to connect with a suitable pipe leading to the contiguous bell or gas-holder. It will be understood that the several bores and branches thereof 46, 47, 48, 49, and 50 may be formed in the casting in any preferred way, the object being to place all of said bores in communication with each other, except as regards the bores 47 and 48, at the point where they cross each other near the middle portion of the casting, it being understood that said bores are so disposed within the casting that they will not tap or lead into each other.

It is obvious that by providing the body-section 45 with the several bores referred to a more desirable grouping of the several parts is effected, thereby making it possible to more readily assemble the complete operative device. The bores 46 and 49 are each provided, at a point intermediate the seals carried by each of said bores, with an extension or neck, the extension 58 being designed to coöperate with the bore 46 and to which the pipe 59, leading to the burner, is attached, while the bore 49 is provided with the extension 60, in proper communication with the supply-pipe 61, as shown in Fig. 4.

I prefer to form upon the lower side of the body-section 45, near each edge thereof, the brackets 62, and pivotally mounted between the same is the supporting-frame 63, and upon each corner of said pipe I provide the sealing-cups 64, each being designed to loosely receive and coöperate with its respective sleeve carried by the body-section 45, it being understood that said body-section is to be held rigidly or permanently in a horizontal position in any preferred way, as by the pipes leading to or from the several extensions 56, 57, 58, and 60.

By reference to Fig. 4 it will be seen that the several sealing-cups 64 are designed to hold the desired quantity of sealing liquid, as mercury or the like, and to be moved so as to bring said liquid into coöperation with the several partitions 55 when the parts are in a sealed position or to be dropped out of contact with said partitions when the seals are open. The outer ends of the frame-section 63 are provided with an arm or bracket 65, to which I pivotally secure the actuating-standards 66, which correspond in function to the standards 30 and 32, (illustrated in Figs. 1 and 2,) the upper ends thereof being designed to contact with the arm or extension 67, carried by the inner edge of the bell 68. Upon the upper side of the body-section 45 I provide the ears or brackets 69, in the upper end of which I mount in suitable bearings a journal or axle 70, having secured thereto the levers or arms 71 and the standard 72, carrying the weight 73, all of said parts corresponding, respectively, to the several parts 24, 25,

26, and 27 of Figs. 1 and 2, adjusting-pins or set-screws 74 being provided in the ends of the lever 71.

In order that a minimum quantity of sealing liquid (indicated 75) may be employed to insure a reliable seal for the telescoping bell or holder 68, I provide the fixed portion or body-section 76 of the holder with an auxiliary internally-disposed chamber 77, which is permanently secured to the bottom of the outer casing or holder 76 in such a manner as to stand equally distant from the internal surface of said holder, and thus provide an annular chamber 78, in which the sealing liquid 75 is disposed, and it is clear that the open end of the telescoping bell will freely rise and fall in the annular chamber thus formed and that a much smaller quantity of sealing liquid will be found amply sufficient to provide a thoroughly-reliable seal than would be the case if the auxiliary chamber 77 were not provided, as shown by holder on left side.

It is clear that the auxiliary chamber 77 may be filled with a heavy substance, or said part may be cast solid and integral with the outer casing, thus giving greater solidity and permanence to said parts. A proper indicator or register 79 may be located upon the edge of the body-section 45 and arranged to be actuated by the spring arms or catches 80 and 81, carried by a contiguous part of the frame-section 63, as by this construction both the upward and downward movements of said frame-section will cause one of the ratchet-teeth of the indicator to be engaged, thereby registering each of said movements instead of registering but one movement when the construction employed in Figs. 1 and 2 is adopted.

By the construction shown in Fig. 4 it will be observed that the telescoping sleeves 6 are dispensed with, in which case the pipes 8 and 9 may be replaced, as by the pipes 82 and 83, the former being a continuation of the pipe 84, leading from the extension 57, while the latter is a continuation of the pipe 85, the upper end of which is in communication with the extension 56. It is obvious that my invention relating to the control of the flow of gas may be used in connection with holders constructed in the form of bellows or collapsing sections in lieu of the telescoping holder and bell, as herein illustrated, and it is also apparent that various modifications may be employed in the construction of the several parts of my improved sealing device and that the manner of mounting the several parts may be varied without departing from the spirit of my invention, and I do not therefore wish to be confined strictly to the exact showing made.

The operation or manner of using the seal shown in Figs. 4, 5, and 6 is substantially the same as the operation described for the construction shown in Figs. 1 and 2, and it is

therefore deemed unnecessary to further elaborate thereon.

Having thus fully described my invention, what I claim as new, and desire to secure by Letters Patent, is—

1. The herein-described cut-off for changing the flow of gas or the like consisting of depending sleeves connected to the service-pipes and having partition-walls therein, in combination with pivotally-mounted sealing-cups and means to move the same, as specified and for the purpose set forth.

2. In an automatic cut-off for gas, the combination with a pair of telescoping holders and suitable pipe connections therefor, said pipe connections having depending sleeves provided with partition-walls therein, of pivotally-mounted members carrying sealing-cups adapted to coöperate with said sleeves and a pivotally-mounted weighted lever and a link connection between said lever and the rim of the holder whereby the downward movement of the holder will actuate said lever and change the position of the sealing-cups, as specified and for the purpose set forth.

3. In a gas-measuring machine, the combination with a pair of telescoping holders pivotally secured together, as specified, of the herein-described automatic cut-off or switch for changing the flow of the gas in the supply-pipe from the full holder to the empty holder without disturbing the supply for the burner, consisting of depending sleeves connected to the supply-pipes and having a partition-wall therein; sealing-cups pivotally held in position in coöperation with said sleeves and means located intermediate the holder and said cups whereby the downward movement of the holder will divert the flow of the gas from the full holder to the empty holder, as specified and for the purpose set forth.

4. The combination with a burner and suitable pipe connections therefor, of the herein-described automatic switch for changing the flow of gas, consisting of a pair of pivoted levers, each carrying a seal upon its free end, all of which are in coöperation with a sealing-sleeve extending from the service-pipes; a link pivotally secured to said levers in such a manner that the movement thereof will be opposite to each other whereby the flow of gas to the burner from the feeding-bell will be cut off at the instant said bell is emptied, and the flow of the gas from the full reservoir directed to said burner, and also that the flow of the gas from the supply-pipe will be turned into the empty bell, all arranged as specified and for the purpose set forth.

5. The herein-described measuring-machine for gas or the like consisting of a pair of telescoping holders, each provided with a suitable service-pipe and sleeve, said service-pipes being connected to each other and with the burner, as specified; depending sleeves

in connection with the service-pipe; a pair of pivoted levers each carrying a sealing-cup designed to coöperate with said sleeves and suitable means intermediate said levers designed to utilize the downward movement of each bell, all arranged as specified and for the purpose set forth.

6. In a gas-measuring machine, the herein-described switching device for changing the flow of gas consisting of depending sleeves formed upon the supply-pipes and a sealing-cup adapted to coöperate with said sleeves and means to simultaneously move said cups in such position as will insure that the flow of gas to the burner from the empty bell will be cut off and the flow of gas from the full bell simultaneously established with said burner, as and for the purpose set forth.

7. The herein-described device for checking and restoring the flow of gas consisting of a sleeve depending from the service-pipe, said sleeve being provided with a diaphragm or partition-wall of shorter reach than said sleeve, and a sealing-cup designed to receive the lower end of said sleeve and contact with said partition when in an elevated position or permit the flow of the gas to pass under the partition when said seal is in a lowered position, as specified and for the purpose set forth.

8. In a measuring-machine for gas, the combination with suitable telescoping reservoirs, of supply-pipes communicating therewith and extending upward between the same; an auxiliary pipe establishing communication between them at a point below the upper end thereof, depending open-ended sleeves having partition-walls, carried by said end and auxiliary pipes, and sealing-cups adapted to receive the open ends of said sleeves and suitable means for utilizing the downward movement of the empty reservoir to so change the position of said cups that the flow of gas from the emptying reservoir to the burner will be cut off and the flow of the gas from the filled reservoir will be established with said burner, and the flow of gas from the supply-pipe directed into the empty reservoir, all operatively combined in the manner and for the purpose specified.

9. In a gas-measuring machine, the herein-described balanced sealing-cups; suitable sleeves carried by the supply-pipes in communication with said cups; counterpoises carried by the supports of said cups whereby the upward or downward movement of the cups will be rendered positive and a controlling-lever having a centrally-disposed counterpoise and adjusting-screws at each end, the

latter designed to contact with the projecting rim of the empty reservoir and means connecting the end of said controlling-lever with said cups whereby the seals will be opened and closed in such a way as to cut off the flow of gas from the empty reservoir with the burner and at the same instant direct the flow from the full reservoir to the burner and from the supply-pipe to the empty reservoir as specified and for the purpose set forth.

10. The herein-described sealing device for gas-machines, consisting of a body-section provided with communicating bores or openings and with supply and discharge apertures; sealing-sleeves having a partition-wall of less extent coöperating with said bores and movable sealing-cups designed to coöperate with said sleeves; a movable bell or holder having an extension or arm, and means located intermediate said arm for coöperating with said movable cups whereby said parts will be automatically controlled to regulate the flow of gas, as specified and for the purpose set forth.

11. The herein-described sealing device for gas consisting of the body-section 45 having a series of communicating bores substantially as specified, a series of depending sleeves in communication with said bores, each sleeve being provided with a partition of less extent than itself, in combination with a pivoted frame or platform located below said body and means carried by said frame to automatically close the open ends of said sleeves whereby the flow of the gas will be controlled in the manner specified and for the purpose set forth.

12. As an improvement in gas-meters, a sealing device consisting of the body-section having a series of communicating bores and feeding and exit apertures in communication therewith, all formed in one piece, a frame-section pivotally mounted in position below said body-section; a series of sealing-cups carried by said frame-section and a series of depending open-ended sleeves having partition-walls secured to said body-section and in communication with the bores thereof whereby said sleeves will be effectually closed when said cups are depressed, all operatively combined in the manner specified and for the purpose set forth.

In testimony whereof I affix my signature in presence of two witnesses.

THEODOR H. J. LECKBAND.
